UNITED STATES PATENT OFFICE.

SAMUEL S. MATTHES, OF MANSFIELD, OHIO, ASSIGNOR TO THE OHIO BRASS COMPANY, OF MANSFIELD, OHIO, A CORPORATION OF NEW JERSEY.

WIRE-CLAMP.

1,367,619.

Specification of Letters Patent.

Patented Feb. 8, 1921.

Application filed September 30, 1920. Serial No. 413,847.

To all whom it may concern:

Be it known that I, SAMUEL S. MATTHES, a citizen of the United States, residing at Mansfield, in the county of Richland and 5 State of Ohio, have invented certain new and useful Improvements in Wire-Clamps, of which the following is a specification.

This invention relates to improvements in supports for trolley wires and particularly 10 those devices generally known as trolley wire clamps.

One object of my invention is to provide a clamp which is simple in construction and easy to assemble in the manufacture; another object is to provide a clamp which is 15 simple in its installation upon the trolley wire and support to which it is attached and efficient in supporting the trolley wire.

The invention consists substantially in the 20 construction, combination, location and arrangement of parts, all of which will be more fully hereinafter set forth, and claimed, and illustrated in the accompanying drawings, in which:—

25 Figure 1 is a side elevation view of my device in partial section and when the parts are in such relation that the jaws may be expanded or opened to their fullest extent.

Fig. 2 is a sectional view of Fig. 1 on the 30 line 2—2.

Fig. 3 is a sectional view of my device showing the parts in such relation as to clamp upon a trolley wire.

Fig. 4 shows a detail in construction 35 which I use in assembling my device and maintaining the parts assembled until installed upon a wire.

Similar numerals refer to similar parts throughout the several views.

40 I provide two complementary jaw members 1—1 and a support member 2 for the device. Means 3 is provided on the support member for securing the device to an overhead support and I have shown this means 45 as an ordinary screw thread which is the most common practice in supporting devices of this character.

To the lower end of the support member 50 is an inverted T shaped projection forming a shelf member 4 secured to the support member by the bridging member 5. The jaws 1 are provided with inwardly projecting supporting members 6 which rest upon the shelf member 4 and pivot or fulcrum at 55 point of contact. The jaw members are also

provided with retaining members 7 which engage with the inner and lower edge of the collar 8 and through this engagement are prevented from being disassembled. The jaw members 1 are also provided with 60 a beveled or conical face 9 which engages with a corresponding face 10 on the collar. The parts 9 and 10 coacting together perform the functions of further preventing the disassembly of the jaws when the collar is moved upwardly to its extreme height 65 and also cause the jaws to grip the trolley wire 17 when the collar member is moved downwardly relatively to the jaws and support member.

At the upper end of the collar is a flange 11 which engages with the lower face of the flange 12 and stops the upward movement of the collar with respect to the support member.

The jaws are further provided at their 70 lower end with means 13 properly formed to engage with a trolley wire and the inner faces of the jaws are provided with horizontal projecting members 14 and 15 which contact with each other to prevent side movement of the jaws relatively to each other and to maintain them better in alinement. The space A in Fig. 1 is occupied by the 75 projecting member 14 on the near side 80 clamp which has been cut away.

In order to assemble this device readily and after assembly to prevent the parts from becoming disassembled, I provide the flange 11 to engage with the flange 12 and 85 the flange 11 is first prepared as shown by numeral 11¹ in Fig. 4. Here it will be seen that the collar 8 may be screwed upwardly 90 on the supporting member 2 until the shoulder 16 engages with the lower face of the flange 12. By comparing this construction with that shown in Fig. 2 it will be noted that in Fig. 4 the parts 16 and 12 can be brought nearer together by the distance 95 shown by the letter B in Fig. 2.

The member 8 is first screwed on to the member 2 until the face 16 contacts with the flange 12. This permits ample room for positioning the jaws 1 in place upon the bridge member 4. The collar 8 is then screwed 100 downward until the upper edge of the flange 11¹ clears the lower face of the flange 12 and then by proper manipulating, the flange 11¹ is caused to be moved inwardly until it underlaps the flange 12. 105 110

This manipulation is brought about by pressing upon the flange 11¹ by suitable dies or by revolving the same in a machine with a tool pressing against the outer edge of the flange 11¹ thereby forcing it inward. When the flange 11¹ has been forced inward a proper distance the collar 8 can be moved upwardly until the flange 11 engages with the flange 12 and the jaws will still be held in an assembled position. (See Fig. 2.)

To assemble the device upon an overhead support and a trolley wire, it is only necessary to rotate the device with the means 3 in engagement with the overhead support until the flange 12 is brought into contact with the face of the hanger or support. If the jaws 13 are now not in alinement with the trolley wire the device is backed off sufficiently to bring about this alinement. The trolley wire 17 is now positioned between the jaws and the collar 8 is rotated and through the medium of the coating thread upon the collar and supporting member the collar is moved downwardly and the parts 9 and 10 engaged, forcing the jaws into engagement with the trolley wire. To bring about a further secure engagement between the jaws and the trolley wire, a wrench is now applied to the collar 8 and by means of the polygonal faces 18 on the collar sufficient force may be applied to cause the jaws to positively and securely grip the wire 17.

There are many modifications which will suggest themselves to those skilled in the art and I do not wish to be limited otherwise than by the following claims.

Claims:—

1. A wire support comprising a supporting member, means to secure the member to a support or hanger, clamping means to engage and hold a conductor, means on the supporting member to engage means on the clamping means and permitting a pivotal action therebetween so that the clamping means can be moved into engagement with the conductor, a collar exterior of the supporting member, means on the supporting member engaging means on the collar causing the collar to move relatively to the clamping means when the collar is rotated in either direction, means on the collar to engage means on the clamping means to move the clamping means into engagement with the conductor when the collar is rotated in one direction and move the collar out of engagement with the clamping means to permit the clamping means to move out of engagement with the conductor when rotated in the opposite direction, means on the clamping means to engage the collar to prevent the removal of the clamping means from its engagement relative to the supporting member and means on the collar engaging means on the supporting member to limit

the relative movement of the parts in one direction.

2. A wire support comprising a supporting member, means to secure the member to a support or hanger, clamping means to engage and hold a conductor, means on the clamping means to engage the supporting member in pivotal relation, a collar arranged to move relatively to the supporting member in either direction when rotated relatively to the supporting member, means on the collar to engage the clamping means to move the clamping means into engagement with the conductor when the collar is rotated relatively to the supporting member in one direction, means on the collar to engage the supporting member to limit the movement of the collar away from the clamping means when the collar is rotated in the opposite direction and means on the clamping means to engage the collar to prevent disengagement of the clamping means relatively to the other parts.

3. A wire clamp comprising a supporting member, means to secure the member to a support or hanger, clamping means to engage and support a conductor and having a pivotal engagement with the supporting member, a collar movable relatively to the supporting member and clamping means when rotated relatively thereto to move the collar into and out of engagement with the clamping means to operate the clamping means, means on the clamping means to engage the collar to prevent the disengagement of the clamping means, means interposed between the collar and supporting member after assembly of the above parts to maintain the parts against separation.

4. A wire support comprising a supporting member, means to secure the member to a support or hanger, a pair of clamping jaws to engage and hold a conductor, means projecting from the supporting member and engaging means on the jaw members in a pivotal relation, a collar movable longitudinally and relatively to the supporting member and rotatable relatively thereto to move the collar into and out of engagement with the clamping jaws to operate the jaws, a beveled exterior surface on each jaw to engage a corresponding interior surface of the collar to operate the jaws, and means on the collar projecting inwardly to engage the supporting member to maintain the parts together after assembling.

5. A wire support comprising in combination a supporting member, means to secure the member to a support or hanger, jaws secured to the supporting member and an operating collar to move the jaws and means on the collar adapted to be turned inwardly after assembly of the parts and engage the support member to lock the parts against separation.

6. A wire support comprising in combination a supporting member, means to secure the member to a support or hanger, jaws secured to the supporting member, an operating collar to move the jaws into engagement with a wire and means adapted to be bent over after the parts have been assembled to limit the relative longitudinal movement of the support member and operating

10 collar.

7. A wire support comprising in combination a supporting member, means to secure the member to a support or hanger, a pair of jaws secured to the supporting member, an operating collar to move the jaws into engagement with the wire and coöperating means on each jaw adjacent the point of

engagement with a wire to prevent relative movement of the jaws at their lower edge.

8. A wire clamp comprising in combination a supporting member, means to secure the member to a support or hanger, an inverted T-shaped member depending from the supporting member, jaws mounted to fulcrum on the inverted T member, means on the T-shaped member to engage means on the jaws to prevent relative rotation of the said member and jaws, an operating collar to move the jaws into engagement with a wire, and means to prevent the separation of the parts after assembly.

In testimony whereof I affix my signature.

SAMUEL S. MATTHIES.
